UNITED STATES PATENT OFFICE.

KENNETH T. MILLER, OF SPRINGFIELD, MASSACHUSETTS.

PLIERS.

Application filed July 3, 1925. Serial No. 41,419.

To all whom it may concern:

Be it known that I, KENNETH T. MILLER, a citizen of the United States, residing at Springfield, in the county of Hampden and State of Massachusetts, have invented new and useful Improvements in Pliers, of which the following is a specification.

This invention relates to improvements in wire working pliers, and is directed more particularly to pliers for removing or stripping the insulating covering from wires, cables, or the like.

The principal object of the invention is the provision of pliers wherein the insulation cutting blades and insulation stripping grippers are arranged so that the insulation is gripped for removal at the time it is being cut, as distinguished from pliers of the prior art wherein the cable is removed from a set of cutting members and then inserted in other stripping members.

With the above objects in view, I am able to produce pliers that are efficient in operation and simple in construction and which are therefore economical to manufacture.

Other objects and advantages will appear from the following description of the invention which is illustrated in the form at present preferred by means of the accompanying drawings, in which:

Fig. 1 is a front elevational view of a pair of pliers embodying my invention; and

Fig. 2 is a rear side elevational view of the jaws of the pliers shown in Fig. 1.

Referring to the drawings in detail, 1 and 2 designate plier handles of usual form that are pivotally connected at 3 in the well-known manner having jaws 4 and 5 carried at the upper ends thereof. Plates 40 or blades 6 and 7 are secured to the jaws 4 and 5 respectively by rivets or the like and are preferably arranged for a shearing action as the handles are moved or pressed together. Notches 8 and 9 are provided on the inner edges of the plates that are sharpened as indicated and adapted for cutting through the insulation of a cable or wire.

The upper notch 8 in each jaw is shown in the form of a V while the notch 9 is semi-circular, but it will be obvious that they may be of any form desired depending upon the use for which the pliers are to be employed.

The sides of the plates below the notch 9 are preferably disposed at an angle relative to one another and are provided with a

beveled cutting edge to form a cutting-off shear. An adjusting screw 10 in threaded engagement with one of the handles is disposed so that its end may abut the other handle and functions as a stop to limit the relative closing movement of the jaws. A lock-nut 11 on the screw is provided for locking the screw in an adjusted position. Gripping members 12 extending transversely of each of the jaws are provided that preferably have a semicircular face that is provided with teeth or serrations, as shown. These gripping members are preferably in alinement with the notch 9 and are adapted to embrace the outer covering of a cable while the covering or insulation is being cut by the cutting edges of the notch. The projections formed by the roughened surface of the gripping members are adapted to pierce the outer covering of the cable to prevent a relative turning or endwise movement of the cable with respect thereto. Gripping members of various forms may be employed that are adapted to embrace and securely grip the cable for the action of the cutting notches.

In operation, the adjusting screw is adjusted so that the jaws and consequently the cutting blades are prevented from cutting through the wire of a cable while of course allowing the cutters to cut through the covering. A covered wire or cable is inserted between the jaws and between the gripping members thereof and the handles pressed together. By this action, the notches of the blades enter and cut through the covering while at the same time the covering is clamped between the grippers to prevent a relative movement of the covering with respect to the jaws. When the handles have been moved to their closed position, the pliers are rotated slightly with respect to the cable so that the covering, being gripped by the jaws, is twisted or turned with respect to the wire. This turning action loosens the covering from the wire and insures a clean continuous cut about the whole circumference of the cable. Finally, the cable is pulled away from the pliers and the portion of the covering behind the blades and embraced by the grippers will be stripped from the wire.

A notch c in a side of one of the jaws is provided and is adapted to scrape and clean the end of the wire when the wire is drawn therethrough.

I am aware that many changes may be

made in the form of the invention without departing from the scope thereof. I therefore prefer to be limited by the appended claims rather than by the foregoing description.

Claims:

1. Pliers of the class described comprising a pair of pivoted handles and jaws operated thereby, blades having complementary cutting notches carried thereby and arranged to cut on opposite sides of the covering of a cable, means for limiting the closing movement of said handles so that the said cutters will not cut through the wire of said cable, and complementary gripping members carried by the jaws at the rear of the blades, and in alignment with the cutting notches thereof for embracing opposite sides of the covering of the cable and arranged to firmly embrace the covering for a twisting action thereof.
2. Pliers of the class described comprising a pair of pivoted jaws and operating handles therefore, blades at the side of said jaws having complementary cutting notches arranged to act on opposite sides of the covering of a cable, complementary gripping members carried by the jaws at the rear of

the blades in alignment with the cutting notches thereof, the said jaws and blades being arranged so that as a cable is gripped between the gripping members the jaws are limited in the closing movement whereby the blades are prevented from shearing off the wire of the cable.

3. Pliers of the class described comprising a pair of pivoted handles and jaws operated thereby, blades carried at the sides of each of the jaws arranged for a shearing action and provided with complementary cutting notches, gripping members in the form of roughened curved seats extending transversely of the jaws and in alignment with the notches of the blades for embracing from opposite sides the covering of a cable while the covering thereof is being cut by the notches of the blades, and an adjusting screw carried by one of said handles arranged to abut the other of said handles to limit the closing movement of the jaws so that the blades will not cut the wire of the cable.

In testimony whereof I have affixed my signature.

KENNETH T. MILLER.
